UNITED STATES PATENT OFFICE.

NELSON J. RUSSELL, OF MINNEAPOLIS, MINNESOTA.

PUMP-ACTUATING MECHANISM FOR CARBURETERS.

1,103,224.

Specification of Letters Patent. Patented July 14, 1914.

Application filed November 29, 1912. Serial No. 734,057.

To all whom it may concern:

Be it known that I, NELSON J. RUSSELL, a citizen of the United States, residing at Minneapolis, in the county of Hennepin and State of Minnesota, have invented certain new and useful Improvements in Pump-Actuating Mechanism for Carbureters; and I do hereby declare the following to be a full, clear, and exact description of the invention, such as will enable others skilled in the art to which it appertains to make and use the same.

My present invention has for its object to provide improved pump actuating mechanism for air carbureting apparatus, the term "pump" being used in a broad sense to include devices for supplying either air or volatile oil under pressure.

Particularly, this invention is in the nature of an improvement on pump actuating mechanism disclosed and claimed in my pending application S. N. 660,915, filed of date, November 17, 1911.

Generally stated, the invention consists of the novel devices and combinations of devices hereinafter described and defined in the claims.

In the accompanying drawings which illustrate the invention, like characters indicate like parts throughout the several views.

Referring to the drawings, Figure 1 is a view in end elevation showing an air carbureting apparatus in which the several features of my invention are incorporated; Figs. 2 and 3 are detail views showing a lever and pawl and ratchet device constituting a novel feature of the pump actuating mechanism; Fig. 4 is a view partly in front elevation and partly in vertical section, and 40 with some parts broken away, showing the carbureting apparatus, and particularly illustrating the pump actuating mechanism; and Fig. 5 is a detail in vertical section taken approximately on the line x^5, x^6 on Fig. 4.

In the type of air carbureting apparatus shown in the drawings, a rotary air supplying and compressing drum 1, constituting an air pump or blower, is arranged to rotate within the water containing tank 2. The drum 1 of this air pump or blower is preferably of a common or standard type, the construction and operation of which is well known to those familiar with carbureting apparatus of this general character. The tank 2 is supported by a suitable framework 3, and the drum 1 has a projecting shaft 4

journaled in the said framework, and, as shown, provided with a small sprocket 5 and with a larger sprocket 6. Secured to one projecting end of the drum shaft 4 is a ratchet wheel 7 having star-pointed teeth. Pivoted on the shaft 4 adjacent to the said ratchet wheel 7 is a hand lever 8 provided with a ratchet dog 9 which will work on the teeth of the ratchet wheel 7 when turned in either direction (see particularly Figs. 2 and 3). The purpose of this lever and pawl and ratchet device will be hereinafter more fully stated.

Mounted in the lower portion of one end of the frame 1, below the shaft 4, is a counter shaft 10, on which a windlass drum 11 may be either loosely mounted, or to which the windlass drum 11 may be keyed. At its left hand end, as viewed in Fig. 4, the windlass drum 11 is provided with a ratchet wheel or ratchet toothed hub 12, and at its right hand end, it is provided with one or more laterally projecting ratchet teeth 13 that constitute what may be termed a half-clutch. Loosely journaled on the shaft 10, adjacent to the ratchet wheel 12 is a large sprocket 14 provided with a spring-pressed dog 15 that engages with the teeth of the said ratchet wheel 12.

A sprocket chain 16 runs over the sprocket 5 of the drum shaft 4 and over the said large sprocket 14. Loosely journaled on the right hand end of the counter shaft 10 is another sprocket 17. This sprocket 17 is free also for lateral movements and is provided with one or more laterally projecting ratchet teeth 18 constituting what may be termed a half-clutch, and arranged for co-operation with the half-clutch 13 on the drum 11. The hub of the sprocket 17 is shown as provided with a circumferential groove 19 with which a shipper lever, not shown, is adapted to engage to impart lateral movements to the said sprocket so as to effect the engagement or disengagement of the half clutches 13 and 18, at will.

A sprocket chain 20 runs over the sprocket 17 and over a small sprocket 21 that is secured to the hub of a spur gear 22. The sprocket and gear 21-22 are journaled on a stud 23 projected from an upward extension of one end of the frame 3. The gear 22 meshes with a spur pinion 24 secured to one end of a short crank shaft 25 journaled in the said end extension of the frame 3 and provided with an operating hand crank 26.

The numeral 27 indicates a mast which is supported by the framework 3 and is provided at its upper end with a head 28 to which is journaled guide sheaves 29.

5 The numeral 30 indicates a cable which is passed over the guide sheaves 29, and is provided at one end with an operating weight 31, and at its other end, is attached to and adapted to be wound upon a windlass drum 11.

10 For supplying the hydro-carbon oil, I preferably employ a cylinder and piston pump 32, and for driving the pump, as well as the blower drum 1, from the weight 31, I 15 advisably use connections best shown in detail in Fig. 5. The cylinder structure of the pump 32 is suitably secured to the framework 3, and the stem 33 of the pump piston is connected by a link 34 to the free end of a lever 35 that is pivoted to the adjacent part of the frame 3. This lever 35 is provided with a longitudinal slot 36 at its free end, that is engaged by the wrist pin 37 of a crank disk or head 38. The 20 crank disk 38, and a small sprocket 39 are both rigidly secured to a short shaft 40 journaled on the adjacent end bracket of the frame 3. A sprocket chain 41 runs over the large sprocket 6 on the drum shaft 4, and 25 over the said small sprocket 39. By the above described arrangement, it is evident that the air pump or blower and the oil pump will be operated at predetermined proportionate speeds.

30 35 Operation: Under the force of the weight 31, the pump or blower drum 3 will be rotated in the direction of the arrow marked on Fig. 1, and under this direction of rotation, the said blower will supply air to the 40 carbureter, not shown. The speed of the rotation of the said blower drum will be controlled in the customary way by the amount of carbureted air or gas used in service, the oil pump 32 will supply oil to the 45 said carbureter, not shown, through suitable and well known connections, not illustrated. When the pump is operative on the blower drum, its power is transmitted from the windlass drum 11 to the 50 sprocket 14, through the pawl and ratchet device 12-15; and at such time, the sprocket 17 is movable laterally out of engagement with the half clutch 13 of the said drum 11, as shown in Fig. 4. When 55 the weight is to be wound up, the sprocket 17 is moved laterally and engages the half clutch 18 with the half clutch 13 of the windlass drum, and then by manipulation of the crank 26, the said windlass drum 60 may be rotated in a direction to wind up the cable 30 thereon, and hence, raise the weight 31. Under this projected rotation of the windlass drum 11, the teeth of the ratchet wheel 12 will slip under the pawl 65 15 and no positive movement will be im-

parted to the blower drum 1 and its shaft 4. However, when the said blower drum is relieved from the force of the propelling weight 31, there will be a tendency to rotate the same backward, due partly to the 70 re-action of the compressed air therein and partly to friction between the driving connections. This backward rotation of the said drum will be positively prevented when the hand lever 8 is dropped onto the 75 stop 8^a on the frame 3, as shown in Fig. 1, and the dog 9 is then turned upward into engagement with the teeth of the ratchet wheel 7, as shown in Fig. 2. This is the position in which the said lever and dog 80 should be set for raising the weight when no gas is being used. When gas is being drawn off or used during the time that the weight is being re-wound, the pressure will rapidly fall, sometimes to such an extent 85 that the lights will go out. To prevent this, the operator, by taking hold of the end of the lever 8 and slowly raising the same, may maintain the normal or desired pressure on the gas while the weight is being raised, by thus imparting a slow rotation to the said blower drum 1 in a forward direction, to-wit, in the direction of the arrow marked on Fig. 1.

90 The ratchet wheel 7, lever 8, and dog 9 95 have another or third highly important function. In cleaning out the machine, the water should be forced out of the blower drum, and this, as is well known, is accomplished by giving the said drum a backward rotation. To impart this backward rotation of the drum, which is always enclosed in an air tight casing, and hence, inaccessible for direct contact, the operator only need first raise the lever 8 and then 100 throw the dog 9 downward and into engagement with the teeth of the ratchet wheel 7, and then by a continued downward movement of the said lever, said blower drum may be positively rotated 110 backward and the water discharged therefrom. When the machine is in normal action from the weight 31, the dog 9 may be turned downward into an idle position, 115 shown in Fig. 1.

What I claim is:

1. The combination with a rotary body, of a power device for rotating said body in an operative direction, means for re-winding or setting said power device without imparting backward rotation to said body, and an auxiliary power device operative, when moved in one direction to rotate said body while said power device is being re-set, operative when held still to prevent 120 rotation of said body, and operative when moved in the opposite direction to impart backward rotation to said body.

2. The combination with a rotary body, of a power device for rotating said body 130

in an operative direction, means for rewinding or setting said power device without imparting backward rotation to said body, and an auxiliary power device operative, 5 when moved in one direction to rotate said body while said power device is being reset, operative when held still to prevent rotation of said body, and operative when moved in the opposite direction to impart 10 backward rotation to said body, said auxiliary power device including an operating pawl and ratchet.

3. The combination with a rotary body, of a power device for rotating said body 15 in an operative direction, means for rewinding or setting said power device without imparting backward rotation to said body, an auxiliary power device operative,

when moved in one direction to rotate said body while said power device is being reset, operative when held still to prevent rotation of said body, and operative when moved in the opposite direction to impart backward rotation to said body, said auxiliary power device including an operating 25 pawl and ratchet, the said pawl being rendered operative when said lever is moved to a predetermined position, and a stop for supporting said lever in said predetermined position.

In testimony whereof I affix my signature in presence of two witnesses.

NELSON J. RUSSELL.
